UNITED STATES PATENT OFFICE.

ARTHUR J. LOMAN, OF UNCASVILLE, CONNECTICUT, ASSIGNOR OF ONE-HALF TO
WILLIAM BROWN, OF UNCASVILLE, CONNECTICUT.

CONTROLLING DEVICE FOR PULP-REFINING ENGINES.

Application filed January 20, 1928. Serial No. 248,071.

This invention relates to certain improvements on means for controlling the operation of that type of pulp refining engines known as Jordan engines, in which a conical 5 grinding roll or plug is mounted for rotation in a casing having an internally conical cooperating bed.

Prior to my invention the position of the plug with relation to the bed has been controlled by an adjusting screw, located at one end of the plug in line with its shaft, adjustment thereof being made to regulate the fineness of the pulp and to take up the wear of the knives, so that the edges of the knives of the plug will be held in the desired relation with those of the bed. In practice the plug is adjusted to a position in which the desired degree of fineness of pulp is secured, but it is largely left to the operators to see that this degree of fineness is maintained. The question as to whether the correct adjustment of the plug is being maintained has usually been determined by two methods, aside from the method of making an examination of the pulp. First by the "feel" of the adjusting screw and second by observation of the load on the motor which is driving the shaft of the grinding plug. That is, the operator can tell, in a general way, by the force required 30 to move the plug towards the bed whether adjustment is necessary by the force required to move it. Also a decrease of the load on the motor, other conditions being unchanged, usually indicates that adjustment is necessary.

Under normal conditions therefore, the force with which the plug must be held up to the bed knives to secure a required condition of pulp is practically constant, and to maintain this constant force with the equipment now in general use is very difficult if not impossible as a practical matter.

The primary object of my invention is to provide means for controlling the position of the grinding plug of a Jordan engine whereby the force with which the plug is held in operative relation with the bed knives is constantly maintained automatically.

I accomplish this object by providing fluid pressure operated means for forcing the plug towards the bed knives, the pressure in which is automatically maintained at a predetermined point, which may be varied according to the conditions required.

For a more complete description of my in-

vention and the means which I preferably employ in connection therewith, reference is made to the accompanying drawing in which:

Fig. 1 is a side elevation of a Jordan engine 60 provided with a preferred embodiment of my invention and

Fig. 2 is a vertical central longitudinal sectional view thereof on a larger scale.

In the drawings 10 indicates the casing of an ordinary pulp refining engine of the Jordan type having an internally conical bed and having a trunco-conical roll, or plug 12 therein, which will be provided with the usual knives on its conical surface adapted to cooperate with the knives of the bed, said plug has axially extending shafts 14 and 15, at its ends, the shaft 14 extending from the smaller end of the plug and an electric motor, or other source of power (not shown) is connected thereto, to drive the same. The shaft 15, in addition to being journalled in the plug casing, is also journalled in a combined journal and thrust bearing 16 of any suitable type, the type shown having the bearing and shaft provided with cooperating annular flanges and grooves.

The bearing 16 is mounted for sliding movement longitudinally of the shaft 15 on a suitable frame or support 18 and is rigidly 85 connected to a piston rod 20 having a double faced piston 21 thereon located in a cylinder 22.

The end of the cylinder opposite the end at which the piston rod enters is in open communication with a pipe 24 having a two way valve 25 therein arranged either to place the cylinder in open communication with a pressure pipe 26, or to open the cylinder to a waste pipe 27. The pipe 26 is connected to an adjustable pressure reducing valve 28, of any well known type which will serve the purpose, having a regulating screw 29, and said valve is in turn connected to any suitable source for supplying water at a constantly maintained pressure, preferably substantially in excess of any pressure which may be required for the purpose, a pump 30 being indicated, for the purpose of illustrating such means.

With the above described arrangement water under a predetermined pressure is delivered from the pressure reducing valve 28, thru pipe 26 to cylinder 22 and the pressure therein acting on piston 21, forces the bear-

ing 16, and consequently the shaft 15 and plug 12, towards the bed knives of the casing, the degree of pressure necessary to force the plug into sufficiently close proximity with the bed knives to secure the desired fineness of pulp being determined by suitable adjustment of the regulating screw 29 of the valve 28.

As the cylinder is thus in constant open communication with a constantly maintained fluid pressure supply, obviously the plug will always be pressed towards the bed knives with the same force, and if leakage should occur at any point, the deficiency will be supplied. Also as the knives on the plug and casing wear down, the pressure will act to move the plug so as to take up this wear so that the results secured will be uniform. A pressure gage 32 is preferably connected to the cylinder and a safety valve 34 may also be connected thereto, to prevent excessive pressure in the cylinder.

As it is at times necessary to move the plug away from the bed knives, a pipe 36 is connected to the pipe 26 and is also connected to the opposite end of the cylinder from that previously referred to through a two way valve 37 which will be normally closed and will normally place this side of the cylinder in open communication with a waste pipe 38.

With this arrangement, if it is desired to move the plug in the direction away from the bed knives, the valve 25 will be opened to waste, so that the piston will be free to move in this direction and the valve 37 will be opened to connect pipe 36 with pipe 26.

With the above described means for controlling the position of the plug, under normal conditions of operation the plug will be practically "floating" that is, under certain conditions of excess load which might tend to cause breakage, the plug will yield, while under other conditions it will be moved towards the bed knives, and under all conditions it will be forced towards the knives with any uniform pressure which conditions may require. While under these conditions, if the pulp supply to the casing should fail, the edges of the knives would be brought into contact and cause excessive wear, the arrangement of the blades is such that they would not interlock and under ordinary conditions, and the plug would be immediately moved back so that the blades would not engage.

By taking note of the pressure required in the cylinder to secure the different degrees of fineness of pulp, or other conditions which may be required, any desired result in this regard may be readily secured by adjusting the pressure reducing valve to maintain the corresponding pressure required.

I claim:

1. In a pulp refining engine, a casing having an internally conical bed, a conical beat-

ing roll arranged therein for axial rotation and for movement axially into operative relation with said bed, and fluid pressure operated means for moving the roll axially towards the bed and for holding it in operative relation therewith under a predetermined pressure. 70

2. In a pulp refining engine a casing having an internally conical bed, a conical beating roll arranged therein for axial rotation and for movement axially into operative relation 75 with said bed, fluid pressure operated means for moving the roll axially towards the bed and automatic means to maintain the fluid pressure in said fluid pressure operated means at a predetermined point, in all positions of 80 the moving parts thereof.

3. In a pulp refining engine, a casing having an internally conical bed, a conical beating roll arranged therein for axial rotation and for movement axially into operative relation 85 with said bed, a fluid pressure chamber having a pressure operated member arranged for engagement with said roll, to move the same into operative relation with said bed, and means to maintain a constant fluid pressure in said chamber to hold the roll in said relation with a constant force. 90

4. In a pulp refining engine, a casing having an internally conical bed, a conical beating roll arranged therein for axial rotation 95 and for movement axially into operative relation with said bed, a fluid pressure chamber having a pressure operated member arranged for engagement with said roll, to move the same into operative relation with said bed, a fluid pressure supply opening to said chamber, 100 a fluid pressure regulator in said supply for controlling the pressure in said chamber and means to adjust said regulator to vary the pressure which is maintained in said chamber. 105

5. In a pulp refining engine, a casing having an internally conical bed, a conical beating roll arranged therein for axial rotation and for movement axially into operative relation 110 with said bed, a fluid pressure chamber having a pressure operated member arranged for engagement with said roll, to move the same into operative relation with said bed, a fluid supply pipe opening to said chamber, a fluid pressure reducing valve connected at its delivery end to said pipe, means for constantly supplying fluid at a relatively high pressure to said reducing valve, and means permitting adjustment of said reducing valve 115 to vary the pressure to be maintained in said chamber. 120

6. In a pulp refining engine, a casing having an internally conical bed, a conical beating roll arranged therein for axial rotation and for movement axially into operative relation with said bed, a fluid pressure chamber having a piston therein, connections between said piston and roll whereby movement of said piston in either direction will 125

cause corresponding movement of said roll to or from said bed, a fluid pressure supply pipe connected to said chamber at each side of said piston, valves in said pipe to control the supply to either side thereof, a fluid pressure regulator connected to said pipe and source of fluid pressure supply connected to said regulator.

7. In a pulp refining engine, a casing having an internally conical bed, a conical beating roll arranged therein and having axially disposed shafts at each end on which it is

rotatably mounted and movable axially, a combined thrust and journal bearing in which one of said shafts is mounted, a piston connected to said bearing, a cylinder in which said piston is located and means to maintain a constant pressure in said cylinder irrespective of the position of the piston therein.

In testimony whereof, I have signed my name to this specification.

ARTHUR J. LOMAN.
